UNITED STATES PATENT OFFICE

FRANK J. GRATHWOL AND JOHN E. GRATHWOL, OF SANDUSKY, OHIO

BEATER ENGINE

Application filed November 29, 1929. Serial No. 410,357.

The present invention relates, as indicated, to a beater engine. The primary object of the invention is to provide a device which shall operate upon straw or other similar material to create a long fibred pulp primarily for use in paper making. Further objects of the invention will appear as the description proceeds. To the accomplishment of the foregoing and related ends, said invention, then, consists of the means herein-after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

20 Fig. 1 is a vertical section through the device of our invention; and Fig. 2 is an elevation of an element comprising a part of the apparatus illustrated in Fig. 1.

Referring more particularly to the drawing, it will be seen that the device comprises a tank indicated generally at 10 and formed of a bottom wall 11, side walls, and one end wall 12 rising substantially vertically from said bottom wall, and a second end wall 13 joined to said bottom wall 11 by a smoothly curved portion 14. The tank or vat is divided into an upper and a lower portion by an intermediate horizontal partition 15 carried by the side walls and terminating short of the end walls 12 and 13.

Adjacent the upper portion of the tank 10 there is mounted a shaft 16 journaled in the side walls of said tank and carrying a plurality of radially projecting arms 17 peripherally spaced about said shaft. In the same vertical plane with said shaft 16 there is mounted a second shaft 18 carrying a similar number of radially projecting arms 19 similarly spaced peripherally about the shaft 18. As is clearly to be seen from an inspection of Fig. 1, the arms 17 and 19 are of a length only slightly less than the distance between the shafts 16 and 18.

Below the partition 15 and in the same vertical plane with the shafts 16 and 18 there

is mounted a third shaft 20 likewise journaled in the side walls of the tank, and provided with radially extending arms 21. A fourth shaft 22 is mounted in the same plane, being journaled in the side walls of the tank and being provided with a plurality of radially extending arms 23. The shafts 20 and 22 are likewise spaced apart a distance only slightly greater than the length of said arms 21 and 23.

Mounted at one side of the vertical plane above mentioned, and journaled in the side walls of the tank, is a shaft 24, means (not shown) being provided for driving said shaft. The shaft 24 carries a pinion 25 in mesh with a gear 26 carried on the shaft 20. Said shaft 20 likewise carries a second gear 27 meshing with a gear 28 of identical pitch diameter carried upon the shaft 22, the mesh of such gears 27 and 28 being such as to prevent interference between the arms 21 and 23.

The shaft 20 carries a third gear 29 of much greater pitch diameter, said gear 29 meshing with a gear 30 having a pitch diameter identical to that of the gear 29 and carried by the shaft 16. Said shaft 16 carries a gear 31 having a pitch diameter equal to that of the gear 27; and said gear 31 meshes with a gear 32 of equal pitch diameter carried upon the shaft 18.

As will be seen, the above described drive mechanism comprises means whereby the shafts 16, 18, 20 and 22 are all driven at the same speed, and whereby the arms on said shafts are prevented from interfering with each other. The shaft 24 is rotated in such a direction as to effect clockwise rotation of the shafts 16 and 22 and counter-clockwise rotation of the shafts 18 and 20.

Mounted upon the partition 15 are a pair of stops 33, one of said stops being positioned adjacent each of the side walls of the tank. Each of said stops 33 is provided with one cam face 34 for cooperation with a wedge 35 having at its upper end a shank 36 threaded for cooperation with a wing nut 37. Said wing nut 37 has bearing against a shield 38 which is supported upon the side walls of the tank and upon the stops 33.

Mounted in horizontal slideways in the side

walls of said tank is a block 39 having at its one end a radiused surface 40 substantially concentric with the shaft 16. Said surface 40 is provided with a plurality of ribs or 5 ridges 41 which, as is most clearly seen in Fig. 2, are angularly related to the shaft 16. In view of the fact that these ridges 41 are formed upon a radiused surface and angle across said surface, it will be seen that any 10 plane including the axis of the shaft 16 will be intersected by an extension of any one of said ribs. A similar block 42 provided with a radiused surface 43 having ridges 44 formed thereon is mounted to slide horizontally upon 15 the partition 15. As will be clearly seen, each of the blocks 39 and 42 is provided at its rear end with a vertical surface with which cooperate the vertical surfaces 46 of the cams 35, whereby said blocks 39 and 42 20 may be adjusted in a horizontal direction by reciprocation of the cams 35 through operation of the wing nuts.

Similarly, a stop 47 having a cammed surface 48 is mounted upon the bottom wall 11 25 of a tank 10, and a wedge 49 is mounted for cooperation with said surface 48 and is provided with a shank 50 extending upwardly through the partition 15 and through an aperture in the shield 38, the upper end 51 of said 30 shank 50 being threaded for cooperation with the wing nut 52 bearing upon said shield 38.

A block 53 is horizontally slidable in guide-ways in the side walls of the tank, and is provided with a radiused portion 54 formed 35 with ribs 55 thereon for cooperation with the arms 21 on the shaft 20. A similar block 56 is horizontally slidable upon the bottom wall 11 of said tank and is formed with a radiused 40 surface 57 provided with ribs 58 thereon for cooperation with the arms 23 on the shaft 22. Each of the blocks 53 and 56 is provided 45 with a vertical surface 59 for cooperation with the corresponding surface 60 on the wedge 49.

In operation, the vat 10 is filled with liquid, as shown, and straw or other similar material is dropped into said tank through the opening 61. The shaft 24 is driven to rotate 50 all of the shafts 16, 18, 20 and 22, so that the arms on said shafts set up a circulation of the liquid through the tank. The straw, carried in the liquid, is caused to move between the arms 17 and the ridges 41 and between 55 the arms 19 and the ridges 44. The wedges 35 are so adjusted that the ends of the arms 17 and 19 barely clear the ridges 41 and 44, so that the straw is rubbed between the arms and the ridges. This operation has a tendency 60 to break down the straw and to tear the fibres thereof apart without cutting the same, so that a long fibred pulp results.

After the straw has passed this stage, the circulation of the liquid in the tank carries 65 the straw around the end 62 of the parti-

tion 15, around the curved portion 14 of the tank wall and into the zone of influence of the arms 21 and 23. It then passes between the arms 21 and the ridges 55 and between the arms 23 and the ridges 58, again being rubbed between the arms and the ridges. 70 Thence the straw moves upwardly past the end 63 of the partition 15 and, if desired, the cycle may be repeated until the pulp is in the desired condition.

Other modes of applying the principle of our invention may be employed instead of the one explained, change being made as regards the mechanism herein disclosed, provided the means stated by any of the following claims or the equivalent of such stated 75 means be employed.

We therefore particularly point out and distinctly claim as our invention:

1. In a device of the class described, a vat, 80 a pair of parallel spaced shafts mounted in said vat in a common vertical plane, a plurality of radially extending arms mounted on each of said shafts, the arms on one shaft 85 radially overlapping those on the other, the length of said arms being slightly less than the distance between said shafts, a block 90 mounted adjacent each of said shafts and formed with a surface cooperable with, but not engageable by said arms, the forward edges of said block being spaced apart a distance equal approximately to the combined diameter of said interfitting rollers and the rear edges forming a reduced passage, said 95 rollers being adapted to rotate in a direction to carry the blades from the wide distance to the narrow opening between the blocks, means for rotating said shafts, said shafts being rotatable to engage floating fiber at the 100 diverging end of said blocks and to discharge it at their convergent ends.

2. In a device of the class described, a vat, 105 a pair of parallel spaced shafts mounted in said vat in a common vertical plane, a plurality of radially extending arms mounted on each of said shafts, a block 110 mounted adjacent each of said shafts and formed with a surface cooperable with but not engageable by said arms, any plane including the axis of either of said shafts being intersected by an extension of said surface on the block adjacent said shaft, and means for rotating said shafts.

3. In a device of the class described, a vat, 115 a plurality of parallel spaced shafts in said vat mounted in a common vertical plane, beater arms on each of said shafts, a block 120 mounted in said vat adjacent each of said shafts, each of said blocks being formed with a concave surface concentric with its respective shaft, and a ridge on each of said concave surfaces and extending almost into the path of the outer ends of said beater arms, said 125 ridges being angularly disposed with respect to said respective shafts.

4. In a device of the character described, a vat adapted to contain a liquid, a pair of parallel shafts mounted in said vat below the level of such liquid, beater arms on each of said shafts, the length of said arms being only slightly less than the distance between said shafts, means cooperable with said beater arms, upon rotation of said shafts, for exerting a mangling effect upon material carried between said arms and said means, and common means for rotating said shafts, said last-named means comprising a driven shaft, a pinion thereon, a gear on one of said pair of shafts meshing with said pinion, a second gear on said one shaft, and a gear on the other of said pair of shafts and meshing with said last-mentioned gear. 70
5. In a device of the character described, a vat, two pairs of parallel shafts mounted in said vat in a common vertical plane, beater arms carried by each of said shafts, the length of such arms being only slightly less than the distance between the shafts of each of said pairs, means cooperable with said arms upon rotation of said shafts for exerting a mangling effect upon material carried between said arms and said means, and common means for driving all of said shafts and for preventing interference between the arms of said respective shafts, comprising a gear carried by each of said shafts, the gears of each of said pairs meshing with each other, a gear of different pitch diameter carried by one of each pair of shafts, said last-mentioned gears meshing with each other, a gear of a third pitch diameter carried by said one shaft of one of said pairs, a driven shaft, and a pinion carried by said driven shaft and meshing with said last-mentioned gear. 80
6. An apparatus of the class described comprising a tank adapted to contain liquid-borne fibers, a pair of beater wheels in said tank, said wheels being adapted to move outwardly in the direction of travel of said fiber, a plurality of ribs arranged in two converging series adjacent the opposite rear quadrants of rotation of said wheels and a discharge channel between the adjacent rear edges of said two series of ribs. 90
7. In an apparatus adapted to comminute water-borne fibers, a tank, a pair of beater wheels completely submerged therein, arms on said wheels partly mutually overlapping, said wheels being adapted to turn outwardly in the direction of travel of said fiber, a plurality of ribs arranged in two converging series adjacent the opposite rear quadrants of rotation of said wheels, and a discharge channel between the adjacent rear edges of said series of ribs. 100
8. An apparatus of the class described comprising a closed liquid circuit, a pair of beater wheels, said wheels carrying arms partly mutually overlapping, said wheels being adapted to turn outwardly in the direction 105
9. An apparatus of the class described comprising a closed liquid circuit, a pair of beater wheels, said wheels carrying arms partly mutually overlapping, said wheels being adapted to turn outwardly in the direction of travel of said fiber, a plurality of ribs arranged in two converging series adjacent the opposite rear quadrants of rotation of said wheels, a discharge channel between the adjacent rear edges of said series, and a pocket 110 below said channel adapted to collect heavy foreign matter. 115
